UNITED STATES PATENT OFFICE

JOSEPH SCHULMAN, OF BROOKLYN, NEW YORK

DESIGN FOR A COMBINED RADIATOR ORNAMENT, PARKING-LIGHT HOLDER, AND FENDER SUPPORT

Application filed November 15, 1929. Serial No. 33,464. Term of patent 14 years.

To all whom it may concern:

Be it known that I, JOSEPH SCHULMAN, a citizen of the United States, and residing in the county of Kings, city of Brooklyn, and State of New York, have invented a new, original, and ornamental Design for the Combined Radiator Ornament, Parking-Light Holder, and Fender Support, of which the following is a specification, reference being had to the accompanying drawings, forming a part thereof.

Figure 1 is a view in front elevation of an

automobile radiator and fenders showing my new design; and

Figure 2 is a view looking from above in Figure 1.

I claim:

The ornamental design for the combined radiator ornament, parking light holder and fender support as shown.

This specification signed this 13th day of November, 1929.

JOSEPH SCHULMAN.
